UNITED STATES PATENT OFFICE.

ADRIAN C. SCHARFF, OF ORANGE, CONNECTICUT.

DESIGN FOR A SMOKER'S STAND.

Application filed April 6, 1927. Serial No. 21,492. Term of patent 3½ years.

To all whom it may concern:

Be it known that I, ADRIAN C. SCHARFF, a citizen of the United States, residing at Orange, county of New Haven, State of Connecticut, have invented a new, original, and ornamental Design for a Smoker's Stand, of which the following is a specification, reference being had to the accompanying drawing, forming part thereof.

The figure is a front elevation of a smoker's stand showing my new design.

The portion shown in full lines is regarded as the dominant feature of the design.

I claim:

The ornamental design for a smoker's stand substantially as shown and described.

ADRIAN C. SCHARFF.
